Patented Mar. 8, 1921.

Application filed September 17, 1920. Serial No. 410,988. Term of patent 3½ years.

To all whom it may concern:

Be it known that I, MAX WILNER, a citizen of the United States, and a resident of the city of New York, borough of Manhattan, county and State of New York, United States of America, have invented a new, original, and ornamental Design for an Article of Manufacture; of which the following is a specification, reference being had to the accompanying drawing, forming a part of the same, wherein—

The figure represents a plan view of my

design as particularly adapted to a border for fabrics for children's skirts.

My design comprises a winter landscape and a grouping of children in winter clothing with a dog and sled in the foreground arranged upon a band forming a border for a child's dress or other fabric.

What I claim and desire to secure by Letters Patent, is:

The ornamental design for an article of manufacture substantially as shown.

MAX WILNER.
